CLAIM

I claim the ornamental design for a gel foot pad, as shown and described.

DESCRIPTION

FIG. 1 is a front-right-top side view of a gel foot pad showing my new design.

FIG. 2 is a top plan view thereof.

FIG. 3 is a bottom plan view thereof.

FIG. 4 is a side view thereof; and,

FIG. 5 is a front view thereof.

The broken line showing of a shoe is for illustrative purposes only and forms no part of the claimed design.
